(57) **CLAIM**

The ornamental design for a cup lid, as shown and described.

DESCRIPTION

FIG. 1 is a perspective view of a cup lid showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the cup lid of FIG. 1 shown in a use configuration with a cup and an utensil as environment; and,

FIG. 9 is another perspective view thereof.

The broken lines and unshaded areas depict portions of the cup lid that form no part of the claimed design.

The broken lines in FIGS. 8-9 illustrate the cup and the utensil as environment that forms no part of the claimed design.
